F. S. HOWE.
CARBURETER.

APPLICATION FILED DEC. 24, 1913.

1,126,218.

Patented Jan. 26, 1915.

UNITED STATES PATENT OFFICE.

FREDERICK S. HOWE, OF MARSHALLTOWN, IOWA.

CARBURETER.

1,126,218.

Specification of Letters Patent.

Patented Jan. 26, 1915.

Application filed December 24, 1913. Serial No. 808,563.

To all whom it may concern:

Be it known that I, FREDERICK S. HOWE, a citizen of the United States, residing at Marshalltown, in the county of Marshall and State of Iowa, have invented certain new and useful Improvements in Carbureters, of which the following is a specification, reference being had to the accompanying drawings.

10. This invention relates to new and useful improvements in carbureters, and more particularly to a carbureter adapted to use kerosene and other similar oils as fuel therein, and the primary object of the invention is to 15. provide an improved carbureter which will materially reduce expense in the operation of an internal combustion engine for automobiles or other uses.

20. A further object of the invention resides in providing a carbureter wherein a tertiary or balancing valve is provided and arranged in a plane in advance of or above the butterfly valve of the carbureter, thereby providing a by-pass for the entrance of fresh 25. air to the carbureter when the butterfly valve is moved from a widely open to a closed position.

30. A still further object of the invention resides in providing a superheating means in connection with the carbureter, and still another object of the invention resides in providing a device which is simple and durable in construction, inexpensive to manufacture, and one which will be very efficient 35. and useful in operation.

With these and other objects in view, the invention consists in the novel features of construction, combination and arrangement of parts as will be hereinafter referred to 40 and more particularly pointed out in the specification and claims.

In the accompanying drawing forming a part of this application, Figure 1 is a vertical longitudinal section through a carbureter constructed in accordance with my invention. Fig. 2 is a horizontal section therethrough as seen on line 2-2, Fig. 1. Fig. 3 is a detail plan view of the operating mechanism for the inlet valve at the carbureting 50 chamber, parts being disclosed in section. Fig. 4 is a detail side elevation thereof.

In describing my invention, I shall refer to the drawing in which similar reference characters indicate corresponding parts throughout the several views and in which 55 1 designates the main housing of the device,

which is formed of an upper and lower section A and B, respectively, secured together in any suitable manner. One portion of this casing or housing is designed to form a float chamber 2, in which is mounted a central shaft 3, and mounted in the chamber is a float 4, that surrounds the shaft 3 and carries an upwardly extending ear 5 to which is pivoted the inner end of an arm 6 fulcrumed intermediate of its ends to a hanger 7 depending from the top of the chamber 2, the outer end of this arm 6 co-operating with a valve member to be presently described.

The bottom of the chamber 2 is provided 70 with a fuel inlet port 8, with which communicates an inlet fuel pipe 9 extending from any source of supply (not shown), and this port 8 terminates in a valve seat 10. A needle valve 11 is adapted to be seated in the 75 valve seat 10, and is threaded intermediate of its ends at 12. A nut 13 or the like is carried by the outer end of the arm 6 and engages with the threaded portion 12 of the needle valve. Encircling the upper portion 80 of the needle valve 11 to rest on the nut 13, is a coil spring 14 and a sleeve nut 15 is engaged with a threaded opening in the top of the float chamber to engage the upper end of the spring 14 and adjust the tension 85 thereof, the upper portion of said needle valve being loosely received through said sleeve nut 15. From the description of the construction of this portion of the device, it will be seen that the amount of fuel to be 90 received in the float chamber 2 may be adjusted, as desired by the adjustment of the sleeve nut 15.

The lower section B of the device has an extension 16 formed thereon which is designed somewhat tubular and extends laterally, the outer termination thereof forming an auxiliary air inlet 17. The upper section A of the casing is also provided with a tubular extension constituting a superheated mixing chamber 18 which is designed to fit over the inner termination of the tubular portion of the extension 16 and the upper termination 19 of the chamber 18, is adapted to connect directly to the intake manifold 100 of the engine. Leading from the bottom of the float chamber 2 and extending through the casing forming the extension 16, is a duct 20, which terminates in a chamber 21 105 formed in the lower portion of the member 18 and will, for convenience, be termed a carbureting chamber.

At the termination of this channel 20 in the chamber 21, a valve seat 22 is formed and I have provided in connection therewith an additional needle valve 23 which is guided through laterally extending arms 24 formed on the member 18. A pivoted collar or the like 25 is carried on this needle valve 23, just above the lower of the pair of arms 24, and encircling the valve between the collar 25 and the upper laterally extending arm 24, is a coil spring 26, the tendency of which is to force the needle valve downwardly so as to engage wholly or partially with the seat 22, as the case may be. Arranged between the arms 24, is a rod 27, on which is mounted a collar or the like 28 against which bears a cam 29. An ear 30 projects upwardly from the upper of the arms 24 and has fulcrumed thereon an L-shaped or bell crank lever 31, the free end of one arm of which is adapted to coöperate with the cam 29, and the free end of the other arm thereof to coöperate with a nut 32 which is adjustably carried on the threaded upper end of the needle valve 23. A throttle lever 33 has connection with the arm 27 and from this construction it will be seen that the needle valve 32 will be raised or lowered as said latter lever is actuated. The cam 29 is capable of adjustment through the medium of a thumb screw 34 threaded into an arm 35 projecting from the collar 28 as clearly shown in Fig. 3.

Pivottally arranged at the lower portion of the chamber 18, is a butterfly valve 35 to which is connected an arm 36 extending on the outside of the chamber. Connected to this arm 36 is a link 37 which also has connection with the arm 38 formed on the collar 28. This butterfly valve, it will be seen, operates with the actuation of the throttle lever and simultaneously with the operation of the needle valve 23.

Leading from the carbureting chamber 21, is a channel 39 which is of predetermined size and preferably tapered toward its outer end at which point it communicates with the interior of the chamber 18, just below the butterfly valve 35. Arranged in the chamber 18, is a superheating coil 40, which leads from the exhaust manifold (not shown) of the engine. The pipe forming this coil may be of any desired material and one terminal extends through an opening 41 in the upper portion of the chamber 18 and the other terminal of the coil leads directly to the carbureting chamber 21 for a purpose to be hereinafter and more particularly set forth.

A lateral extension or the like 41' is provided on the upper portion of the chamber 18 and constitutes an air chamber and has an inwardly opening valve 42 arranged in connection therewith. This valve is normally held in its closed position by means

of a spring 43 which coöperates with one face of the valve 42 and an enlarged upper end of an adjustable stem 44, the latter being threaded into engagement with a threaded opening in the lower wall of the extension 41', the valve constituting an air governing valve. This valve, which forms the tertiary or balancing valve of the carbureter is disposed in a plane above the plane of the butterfly valve and in the disposition of said latter valve, from a widely open to a closed position, a fresh supply of air is admitted to the carbureter and an overloading of a rich mixture to the device, as is true in most carbureters, under these conditions, is obviated. In view of these conditions, carbonizing of the cylinders and the fouling of the spark plugs is prevented and cool air is admitted to the device, thus preventing the undue heating of the motor.

This device, as indicated above, is adapted for use in connection with kerosene or like oils and in the operation of the device the fuel enters the float chamber 2, through the inlet port 8, from the source of supply. The fuel will flow into the chamber 2 to raise the float 4 and on reaching a predetermined level will cause the float to rise to such an extent as to dispose the needle valve 11 to its closed position in the seat 10. The fuel will then flow through the duct 20 to the carbureting chamber 21. The fuel emptying into the chamber 21 is mixed with the hot air which is also emptied into said chamber from the superheating coil 40, it being understood that the latter connects with the exhaust of the engine, and the mixture of the fuel and hot air is passed out through the channel-way 39 into the hollow or tubular portion of the extension 16. At this time the mixture combines with the air which is drawn therein through the auxiliary air inlet 17 and is atomized, it being understood that the butterfly valve 35 is disposed to its open or partially open position, and this atomized mixture then passes to the superheating mixing chamber. As this mixture rises in the last mentioned chamber, the same again mixes with the additional air drawn in the device through the opening of the balancing or tertiary valve 42 and this mixture is then complete and ready to be passed to the engine directly at the opening in the end 19. The mixture is correct for the speed desired for the engine. When it is desired to decrease the speed of the engine the throttle lever is, of course, actuated, which tends to close the butterfly valve 35 and when this valve is closed, as stated above, a fresh supply of air is introduced into the device through the opening of the valve 42 and, in this manner, the overloading of a rich mixture into the device, under such conditions, is prevented. This is true in view of the particular position of the valve 42 with respect to the butterfly valve 35 and

the other advantages of such positioning of the valves with respect to one another are also true, as previously stated. It will also be noted that the valve 42 acts as an air cushion to the motor and gives greater flexibility of the control thereof and in view of the many advantages set forth for this valve the same may be considered a governor valve. The needle valve 23 will, obviously, 10 be actuated simultaneously with the actuation of the throttle lever, in view of the particular construction of the parts in connection therewith, as previously described.

From the foregoing, it will be seen that I 15 have provided a simple, inexpensive and efficient means for carrying out the objects of the invention and while I have particularly described the elements best adapted to perform the functions set forth, it is obvious 20 that various changes in form, proportion and in the minor details of construction may be resorted to without departing from the spirit or sacrificing any of the principles of the invention.

Having thus described this invention, 25 what I claim is:—

1. A carbureter of the class described comprising a float chamber, a carbureting chamber, an air inlet, a superheating mixing 30 chamber in communication with the air inlet and carbureting chamber, a throttle valve arranged at the lower end of said superheating mixing chamber, means actuated by the adjustment of the throttle valve 35 to control the feed of the fuel to the carbureting chamber, and an additional air inlet arranged in a plane above said throttle valve.

2. A carbureter of the class described comprising a float chamber, a carbureting chamber communicating therewith, an air inlet, a superheating mixing chamber communicating with the air inlet and carbureting chamber, a throttle valve arranged at the lower 40 end of said superheating mixing chamber, means actuated by the adjustment of the throttle valve to control the feed of the fuel 45

to the carbureting chamber, and an additional air inlet arranged in a plane above said superheating mixing chamber. 50

3. In a carbureter of the class described, a float chamber, a carbureting chamber communicating therewith, an air inlet, a throttle valve, a needle valve to control the flow of fuel from the float chamber to the carbureting chamber, means for simultaneously actuating said throttle and needle valves, and an additional air inlet arranged in a plane above said throttle valve. 55

4. In a carbureter of the class described, a float chamber, a carbureting chamber having communication therewith, an air inlet, means to supply superheated air to the carbureting chamber, a superheating mixing chamber having communication with the carbureting chamber and air inlet, a throttle valve arranged at the lower end of said superheating mixing chamber, means actuated by the adjustment of the throttle valve 65 to control the feed of the fuel to the carbureting chamber, and an additional air inlet arranged above said superheating mixing chamber. 70

5. A carbureter of the class described comprising a float chamber, a carbureting chamber communicating therewith, an air inlet, a superheating mixing chamber communicating with the air inlet, said carbureting chamber being provided with a restricted outlet channel tapering in width greater toward 75 its outer end and terminating at a point adjacent the lower end of the superheating mixing chamber, a throttle valve arranged at the lower end of said superheating mixing chamber, just above the termination of the aforesaid restricted outlet channel, and an additional air inlet arranged in a plane above said superheating mixing chamber. 80

In testimony whereof I hereunto affix my signature in the presence of two witnesses. 85
